(57) **CLAIM**

The ornamental design for a display screen or portion thereof with animated graphical user interface, as shown and described.

DESCRIPTION

Design 1: Reproduction 1.1 is a first image in a sequence; Reproduction 1.2 is a second image thereof; and Reproduction 1.3 is a third image thereof;

Design 2: Reproduction 2.1 is a first image in a sequence; Reproduction 2.2 is a second image thereof; and Reproduction 2.3 is a third image thereof;

Design 3: Reproduction 3.1 is a first image in a sequence; Reproduction 3.2 is a second image thereof; and Reproduction 3.3 is a third image thereof.

The broken lines showing a display screen or portion thereof and portions of the graphical user interface form no part of the claimed design.

The appearance of the transitional image sequentially transitions between the images shown in Reproductions 1.1-1.3,

(Continued)

2.1-2.3, and **3.1-3.3**. The process or period in which one image transitions to another image forms no part of the claimed design.
